UNITED STATES PATENT OFFICE

ALBERT BORNSTEIN, OF WESTWOOD, NEW JERSEY

DESIGN FOR A LAMP

Application filed January 21, 1931. Serial No. 38,405. Term of patent 7 years.

To all whom it may concern:

Be it known that I, ALBERT BORNSTEIN, a citizen of the United States, and resident of Westwood, in the county of Bergen and State of New Jersey, have invented a new, original, and ornamental Design for Lamps, of which the following is a specification, reference being had to the accompanying drawings, forming part thereof.

Fig. 1 is a perspective view of my invention.

Fig. 2 presents a front view thereof.

Fig. 3 shows a side view of the present design.

I claim:

The ornamental design for a lamp, as shown.

Signed at New York city, in the county of the Bronx and State of New York, this tenth day of January, A. D. 1931.

ALBERT BORNSTEIN.
